RAILWAY-TRAFFIC-CONTROLLING APPARATUS.

1,333,642.

Specification of Letters Patent. Patented Mar. 16, 1920.

Application filed October 2, 1919. Serial No. 327,990.

To all whom it may concern:

Be it known that I, CLARENCE S. SNAVELY, a citizen of the United States, residing at Pittsburgh, in the county of Allegheny and 5 State of Pennsylvania, have invented certain new and useful Improvements in Railway-Traffic-Controlling Apparatus, of which the following is a specification.

My invention relates to railway traffic controlling apparatus, and particularly to apparatus wherein a plurality of railway switches are controlled from a central point. Apparatus embodying my invention is especially adapted for the control of switches in freight 15 classification yards, although it is not limited to this adaptation.

I will describe two forms of apparatus embodying my invention, and will then point out the novel features thereof in claims.

20 In the accompanying drawings, Figure 1 is a view, partly diagrammatic and partly in perspective, showing one form of apparatus embodying my invention. Fig. 2 is a view showing in front elevation one machine unit 25 comprised in the apparatus shown in Fig. 1. Fig. 3 is a top view of the machine unit shown in Figs. 1 and 2.

Similar reference characters refer to similar parts in each of the views.

30 Referring first to Fig. 1, the reference character A designates a railway switch which is operated by a fluid pressure motor device B, and which motor device is in turn controlled by a circuit controller C forming 35 part of a machine unit which is designated as a whole by the reference character D.

The motor device B comprises a piston 1 reciprocating in a cylinder 2 and operatively connected with the movable rails of the 40 switch A. Fluid pressure is admitted to the ends of the cylinder 2 by means of valves controlled by two magnets N^a and R^a, the operation being such that the switch is moved in one direction or the other according 45 as magnet N^a or magnet R^a is energized.

The machine unit D comprises a shaft 6 mounted to rock between two extreme positions on a longitudinal axis, and which shaft operates the circuit controller C. This 50 circuit controller comprises a contact finger 3 which is actuated by the shaft 6 and is moved into engagement with a fixed contact 4 or a fixed contact 5 according as the shaft is rocked to one extreme position or the other.

As shown in Fig. 1, shaft 6 is rocked to its 55 extreme left-hand position, which I will term the "normal" position, wherein contact 3—5 is closed. This causes magnet N^a to be energized, the circuit being from a battery F through wires 10 and 10^a, contact 3—5, wire 60 12, magnet N^a, and common wire O to battery F. Fluid pressure is thus admitted to the upper end of cylinder 2, so that switch A is held in the position shown, which I will term the "normal" position. When shaft 65 6 is moved to its other extreme or "reverse" position, contact 3—5 will be opened and contact 3—4 will be closed, whereupon magnet R^a will become energized through wire 11 and magnet N^a will become deenergized. 70 Fluid pressure will then be admitted to the lower end of cylinder 2 so that switch A will be moved to its other extreme position, which I will term the "reverse" position. Magnets N^a and R^a may appropriately be termed the 75 normal and reverse magnets, respectively. The shaft 16 is provided with a suitable operating handle 13.

The movements of shaft 6 are governed by a neutral armature 7 controlled by an electro-magnet E. This armature is provided with a tongue 8 co-operating with a dog 9 on the shaft in such manner that the shaft is locked in either extreme position when the magnet is deenergized, but that the shaft is released 85 when the magnet is energized. This armature also operates a disk indicator 19 through a link mechanism 20, whereby the indicator is moved into and out of a visible position behind an opening 21 (see Fig. 2) according 90 to as the magnet E is deenergized or energized.

The magnet E also controls a polarized armature P which, as here shown, is in the form of a permanent horseshoe magnet. This armature is pivotally mounted on a vertical axis at 22 and 22^a to swing between the pole-pieces of the magnet, so that when the north pole is adjacent either pole-piece the south pole is adjacent the other pole-piece. It follows that this polarized armature will swing in one direction or the other according as magnet E is supplied with current of one polarity or the other. As here shown, (see Fig. 3) armature P is biased to a middle position by a spring 23, so that it 10 assumes this position when the magnet is partially or wholly deenergized in accordance with operation hereinafter described,

although in one embodiment of my invention this biasing means may be omitted as hereinafter pointed out. Armature P carries a pointer 24 which swings behind an opening 25, and which pointer occupies a position over the letter N or the letter R, according as the armature is swung to one extreme position or the other; the pointer is, of course, midway between these two letters when the armature is in its middle or biased position.

Magnet E is provided with a circuit which includes a pole-changer G operated by the switch A as hereinafter explained, and the rails of a section of track J-K located adjacent the switch. With the switch in the position shown, this circuit is from battery F, through wires 10 and 26, resistance 27, wire 26^a, track rail 28, wire 29, contact 46-47, wires 50^a and 50, pole-changer G, wire 33, winding of magnet E, wire 32, pole-changer G, wire 36, track rail 28^a, and wires 37 and O to battery F. The switch being in normal position, magnet E is then energized in such direction that pointer 24 is over the letter N. When the switch is reversed, the circuit will be the same, except that it will include a contact 46-49 and wire 50^a instead of contact 46-47 and contact 50^b, as hereinafter explained, and except that current of the opposite polarity will be supplied to magnet E owing to the reversal of pole-changer G, whereby pointer 24 will move to a position over the letter R.

The mechanism interposed between switch A and pole-changer G is as follows: Operatively connected with the switch rails is a motion plate 38 having a cam slot 39 shaped as shown. Co-acting with the cam slot is a roller 41 carried by a bar 40 which is mounted for transverse movement with respect to the movement of the motion plate. The bar 40 is provided with a tongue 40^a which is located between two springs 42 and 42^a mounted in a yoke on a member 43 which operates the contacts of pole-changer G. The movements of member 43 are controlled by a rod 44 which moves in unison with the motion plate 38. Rod 44 carries a dog 44^a which coacts with a dog 43^a on member 43 to prevent movement of the latter member except when the switch is in one extreme position or the other. The operation of this mechanism is as follows: When the switch is in the normal position, the motion plate 38 is in its lowest position, as shown, so that contact operating member 43 is at the extreme right. When the switch A begins to move toward the reverse position, dog 44^a on rod 44 moves into the path of dog 43^a, thereby locking the operating member 43. During the movement of the switch, bar 40 is moved to the left, thereby compressing spring 42,

and upon the completion of the movement of the switch, dog 44^a moves out of the path of dog 43^a, so that the operating member 43 moves to its extreme left-hand position with a snap action under the influence of spring 42. It will be seen, therefore, that pole-changer G occupies one position or the other according as the switch is in normal or reverse position, and that this pole-changer is not reversed until the completion of a full movement of the switch, whereupon the reversal of the pole-changer takes place with a snap action.

The circuit for magnet E is controlled by the switch in such manner that a resistance 45 is included in this circuit whenever the switch is in any intermediate position, but that this resistance is bridged by a low-resistance shunt when the switch occupies its normal or its reverse position. As here shown, this is accomplished by two contact members 47 and 49 attached to the motion plate 38 and co-operating with a contact finger 46. When the switch is in the normal position, the circuit for magnet E passes from wire 29, through contact finger 46, contact member 47, and wire 50^b to wire 50. It will be seen that at such time, a low resistance shunt is closed around resistance 45 so that this resistance is in effect excluded from the circuit. When switch A is in its reverse position, the magnet circuit passes from wire 29, through contact finger 46, contact member 49, and wire 50^a to wire 50. With the switch in this position, therefore, the resistance is again in effect excluded from the circuit. When the switch occupies any intermediate position, however, contact 46 is not in engagement with either contact 47 or 49, so that resistance 45 is then included in the circuit of magnet E, the path being from wire 29 through resistance 45 to wire 50.

The parts of the apparatus are so designed and proportioned that if resistance 45 is included in the circuit for magnet E while armature 7 is closed, the consequent diminution of the current flowing in this circuit will not be sufficient to cause this armature to release. This diminution of current will, however, be sufficient to permit the polarized armature P to move to its middle position under the influence of the biasing spring 23. In other words, the current which flows in the indication circuit when resistance 45 is included in this circuit, is above the releasing point of neutral armature 7 but below the releasing point of polarized armature P. It is, of course, understood that when a car enters track section J-K, it will substantially short circuit the winding of magnet E, so that neutral armature 7 and polarized armature P will both release. The consequent opening of armature 7 locks the circuit controller

shaft 6 in whichever extreme position it may occupy.

The operation of the apparatus is as follows: As shown in the drawing, the switch 5 A is in its normal position and the other parts of the apparatus are in their positions corresponding to this position of the switch. Armature 7 is closed, so that lever 6 is unlocked and armature P is swung in such direction that pointer 24 is over the letter "N" on the front plate of the machine unit. When it is desired to reverse the switch A, the operator rocks the shaft 6 in clockwise direction, thereby shifting contact 3 of circuit controller C into engagement with contact 4. The consequent deenergization of normal magnet N^a and the energization of reverse magnet R^a causes the motor device B to move switch A to its reverse position. 10 As soon as the switch leaves its normal position, the low resistance shunt around resistance 45 is opened, so that polarized armature P moves to its middle position where in the pointer 24 is between the letters "N" 15 and "R". When the movement of the switch has been completed, pole-changer G reverses with a snap action, and at the same time a low resistance shunt is closed around resistance 45, so that polarized armature P is 20 swung to the position wherein pointer 24 is above the letter "R". It will be noted that during this entire operation the indication circuit is closed except for an instant during the reversal of pole-changer G. Indicator 25 19, therefore, moves into its position behind the opening 21 for only an instant upon completion of the movement of the switch.

The operation of the apparatus during a movement of the switch A from reverse to normal position will be understood from the foregoing without further explanation.

It will be observed that failure of the switch to complete its movement will not open the circuit for magnet E, and, consequently, I am enabled to utilize the neutral armature 7 and the disk 19 moved thereby as a track indicator, for the reason that the shunting of the track circuit alone will cause armature 7 to release.

50 In the event that the shaft 6 is reversed and the switch does not respond, the shaft will be left in one position with the pointer 24 in the opposite position, thus showing at once that the switch has failed to operate. 55 The switch can then be tried several times by throwing the shaft 6 back and forth, and as soon as the indicator 24 begins to follow the movement of the shaft it will be known that the switch is again in operation. Furthermore, if any question arises as to whether or not the switch is operating properly, it is only necessary to rock the shaft 6 noting the action or inaction of the pointer 24. One advantage of the apparatus disclosed 60 herein is that the pointer 24 will always in-

dicate the last position of the switch previous to a failure of the switch to respond to the operation of the control lever, and hence will give the operator information as to the safest position in which to place the shaft 6 when a car is approaching the switch in order to avoid the possibility of the switch moving under the car.

It will be observed that the combination of the snap pole-changer operated by the switch, together with the machine unit shown in the accompanying drawings, will, with only two wires between the switch and the unit, give separate indications of the condition of the track circuit and the position of the switch, and will provide for locking of the circuit controller C due to a car approaching the switch. The circuit controller is, however, not in any way tied up due to a failure of the switch. 85

In some instances it may not be considered necessary to cause the pointer 24 to assume an intermediate position during the operation of the switch, and in such instances the resistance 45 may be omitted and wires 90 29 and 50 may be joined by a wire 51, which is shown in dotted lines in Fig. 1. Contact members 47, 48 and 49, together with contact finger 46, may then be omitted, and the spring 23 for biasing the polarized armature P to its middle position may likewise be omitted. With the apparatus arranged in this manner the operation would be the same as explained hereinbefore, with the exception that upon reversal of the switch the 10 pointer 24 will not move until the operation of the switch has been completed.

Considering the machine unit in itself, one important feature is the provision of a long thin magnet of the horseshoe type as a 10 polarized armature. Due to the length of this magnet its calibration will remain more nearly constant throughout its life than is the case with a short flat magnet of the type generally used in polarized apparatus. 11 Furthermore, the possibility of the polarity of the magnet P reversing is reduced, because of the large magnetomotive force and reluctance of this magnet. The structure of the machine unit permits the direct 11 mounting of the pointer 24 upon armature P, and so avoids the necessity for extra bearings.

It is, of course, understood that the fluid pressure motor B may be replaced by any 12 type of motor device which can be controlled by circuit controller C of the machine unit D.

Although I have herein shown and described only two forms of apparatus embodying my invention, it is understood that various changes and modifications may be made therein within the scope of the appended claims without departing from the spirit and scope of my invention. 13

Having thus described my invention, what I claim is:

1. Railway traffic controlling apparatus comprising a railway switch having normal and reverse positions, a circuit controller for governing said switch and having normal and reverse positions corresponding to the positions of the switch, a circuit including the rails of a section of track adjacent said switch, a pole-changer in said circuit and operated by said switch to occupy one extreme position or the other according as the switch is in normal or reverse position, a magnet included in said circuit, means including a neutral armature controlled by said magnet for locking said circuit controller when the magnet is deenergized, and means including a polarized armature controlled by said magnet for indicating the position of the switch.

2. Railway traffic controlling apparatus comprising a railway switch, a circuit controller for governing said switch; a circuit including the rails of a section of track adjacent said switch, a pole-changer operated by the switch, and an electromagnet; means including a neutral armature controlled by said magnet for locking said circuit controller when the magnet is deenergized, and means including a polarized armature controlled by said magnet for indicating the position of said switch.

3. Railway traffic controlling apparatus comprising a railway switch, a circuit controller for governing said switch; a circuit including the rails of a section of track adjacent said switch, a pole-changer operated by the switch, and an electromagnet; means including a neutral armature controlled by said magnet for locking said circuit controller when the magnet is deenergized, an indicator controlled by said neutral armature for showing whether said circuit controller is locked or released, and means including a polarized armature controlled by said magnet for indicating the position of said switch.

4. Railway traffic controlling apparatus comprising a railway switch; a circuit including the rails of a section of track adjacent said switch, a pole-changer operated by the switch, and a magnet; means including a neutral armature controlled by said magnet for indicating whether or not said track section is occupied, and means including a polarized armature controlled by said magnet for indicating the position of said switch.

5. Railway traffic controlling apparatus comprising a railway switch, a circuit controller for governing said switch, a pole-changer, means controlled by said switch for reversing said pole-changer with a snap action upon the completion of each movement of the switch, an electromagnet; a cir-

cuit including said pole-changer, said electromagnet, and the rails of a section of track adjacent the switch; means including a neutral armature controlled by said magnet for locking said circuit controller, and means including a polarized armature controlled by said magnet for indicating the position of said switch.

6. Railway traffic controlling apparatus comprising a railway switch, a circuit controller for governing said switch, a pole-changer operatively connected with said switch to occupy one extreme position or the other according as the switch is in one extreme position or the other and to reverse 80 with a snap action upon completion of a movement of the switch, an electromagnet; a circuit including said pole-changer, said electromagnet, and the rails of a section of track adjacent the switch; means including 85 a neutral armature controlled by said magnet for locking said circuit controller, and means including a polarized armature controlled by said magnet for indicating the position of said switch.

7. Railway traffic controlling apparatus comprising a railway switch, a circuit controller for governing said switch; a circuit including the rails of a section of track adjacent said switch, a magnet, and a pole- 90 changer operated by said switch and reversed upon the completion of a movement of the switch; means controlled by the switch for inserting a resistance in said circuit when the switch is not in one extreme 100 position or the other, means including a neutral armature controlled by said magnet for locking said circuit controller when the magnet is deenergized, a polarized armature controlled by said magnet and biased to a 105 middle position and movable in one direction or the other therefrom according to the polarity of the current supplied to said magnet, and an indicator controlled by said polarized armature for showing the position 110 of the switch.

8. Railway traffic controlling apparatus comprising a railway switch, a circuit controller for governing said switch; a circuit including the rails of a section of track adjacent said switch, a magnet, and a pole- 115 changer operated by said switch and reversed upon the completion of a movement of the switch; means controlled by the switch for inserting a resistance in said circuit when the switch is not in one extreme 120 position or the other, means including a neutral armature controlled by said magnet for locking said circuit controller when the magnet is deenergized, a polarized armature 125 controlled by said magnet and biased to a middle position and movable in one direction or the other therefrom according to the polarity of the current supplied to said magnet, and an indicator controlled by said 130

polarized armature for showing the position of the switch, the parts being so proportioned that when said resistance is excluded from the circuit both of said armatures are 5 actuated, and that when the resistance is included in the circuit the polarized armature releases but the neutral armature does not release.

9. Railway traffic controlling apparatus 10 comprising a railway switch, a circuit controller for governing said switch; a circuit including the rails of a section of track adjacent said switch, a magnet, and a pole-changer operated by said switch and reversed upon the completion of a movement 15 of the switch; means controlled by the switch for inserting a resistance in said circuit when the switch is not in one extreme position or the other, means including a neutral armature controlled by said magnet for indicating whether or not said track section 20 is occupied, a polarized armature controlled by said magnet and biased to a middle position and movable in one direction or 25 the other therefrom according to the polarity of the current supplied to said magnet, and an indicator controlled by said polarized armature for showing the position of the switch.

30 10. In combination, a railway switch, a pole-changer operated thereby, a circuit including said pole-changer and the rails of a section of track adjacent said switch, means controlled by said circuit and responsive to the presence or absence of current for 35 indicating the presence and absence of a car in said track section, and means controlled by said circuit and responsive to reversals of current polarity for indicating the position of said switch.

11. In combination, a railway switch, a circuit controller for governing the same, a pole-changer operated by said switch, a circuit including said pole-changer and the 45 rails of a section of track adjacent said switch, means controlled by said circuit and responsive to the presence and absence of current for locking said circuit controller, and means controlled by said circuit and responsive to reversals of current polarity for indicating the position of said switch.

12. In combination, a railway switch, a pole-changer operated thereby and arranged to be reversed with a snap action upon the 55 completion of a movement of the switch, a circuit including said pole-changer and the rails of a section of track adjacent the switch, means controlled by said switch for inserting a resistance in said circuit when 60 the switch is not in either extreme position, means controlled by said circuit and responsive to the presence or absence of current but not to the diminution of current due to insertion of said resistance for indicating the presence and absence of a car in 65

said track section, and means controlled by said circuit and responsive to reversals of current polarity and to diminution of current due to insertion of said resistance for indicating the position of the switch. 70

13. In combination, a railway switch, a pole-changer operated thereby and arranged to be reversed upon the completion of each movement of the switch, a circuit including 75 said pole-changer and the rails of a section of track adjacent said switch, means controlled by said switch for diminishing the current in said circuit when the switch is not in either extreme position, means controlled by said circuit and responsive to the 80 presence or absence of current but not to diminution of current for indicating the presence or absence of a car in said track section, and means controlled by said circuit and responsive to reversals of current 85 and to diminution of current for indicating the position of said switch.

14. In combination, a railway switch, a circuit controller for governing said switch, a pole-changer operated by the switch and arranged to be reversed upon the completion of each movement of the switch, a circuit including 90 said pole-changer and the rails of a section of track adjacent said switch, means controlled by said switch for diminishing the current in said circuit when the switch is not in either extreme position, means controlled by said circuit and responsive to the presence or absence of current but not to diminution of current for 95 locking said circuit controller, and means controlled by said circuit and responsive to reversals of current and to diminution of current for indicating the position of said switch. 100

15. In combination, a railway switch, a circuit including the rails of a section of track adjacent said switch, means controlled by said switch for diminishing the current in said circuit when the switch is not in 110 either extreme position, means controlled by said circuit and responsive to the presence or absence of current for indicating the presence or absence of a car in said track section, and means controlled by said track 115 circuit and responsive to diminution of current for indicating the position of said switch.

16. In combination, a railway switch, a pole-changer operated thereby and arranged to be reversed upon the completion of each movement of the switch, a circuit including 120 said pole-changer and the rails of a section of track adjacent said switch, means controlled by said switch for diminishing the current in said circuit when the switch is not in either extreme position, means controlled by said circuit and responsive to the presence or absence of current for indicating the presence or absence of a car in said 125

track section, and an indicator controlled by said circuit and arranged to occupy one extreme position or another according as said pole-changer occupies one position or another and an intermediate position when the current in said circuit is diminished.

17. In combination, a railway switch, a circuit, means controlled by said switch for diminishing the current in said circuit when the switch is not in either extreme position, and means controlled by said circuit and responsive to diminution of current for indicating the position of said switch.

18. In combination, a railway switch, a pole-changer operated thereby and arranged

to be reversed upon the completion of each movement of the switch, a circuit including said pole-changer, means controlled by said switch for diminishing the current in said circuit when the switch is not in either extreme position, and means controlled by said circuit and responsive to reversals of current and to diminution of current for indicating the position of said switch. 20

In testimony whereof I affix my signature 25
in presence of two witnesses.
